SEAL

Walter W. Meyer, Arlington Heights, Ill., assignor
to Rotary Seal Company, Chicago, Ill., a corpora-
tion of Illinois

Application June 15, 1939, Serial No. 279,295

6 Claims. (Cl. 285—97.3)

My invention relates in general to seals and sealing and has more particular reference to the provision of means for sealing relatively rotatable, interconnected conduit-forming portions at the connection thereof.

An important object of the present invention is to provide for sealing a rotatable pipe or conduit within a relatively stationary casing; a further important object being to provide improved means sealed against leakage for introducing liquid to rotating elements; a still further object being to provide means for delivering cooling liquid, such as water, from a source comprising stationary mains, into a rotating element, such as a drum or roller required to be cooled.

Another important object resides in providing a seal of the character described, wherein the fluid is delivered to a rotating pipe or conduit extending within a casing, and wherein annular sealing means through which the pipe or conduit extends is employed to form a liquid-tight seal between the conduit and the surrounding surfaces of the shell or casing; a further object being to provide means for delivering fluid to rotating elements, including a delivery casing, and means to seal the casing upon a pipe or conduit which rotates with the rotating receiver, wherein the sealing means serves also to support the casing on said rotating conduit, including flexible means for delivering fluid to the casing for transfer thence through the rotating pipe or conduit to the point of delivery.

Another important object resides in the provision of means for yieldingly journaling the rotatable conduit within the delivery casing and at the same time to provide a self-aligning seal providing adequate sealing at all times, regardless of relative wobble of the casing with respect to the conduit.

These and numerous other important objects, advantages and inherent functions of the invention will become apparent as the same is more fully understood from the following description, which, taken in connection with the accompanying drawing, discloses a preferred embodiment of the invention.

Referring to the drawing,

Figure 1 is a sectional view through sealed delivery means embodying my present invention; and

Figure 2 is an assembly view showing in perspective parts forming the seal illustrated in Figure 1.

To illustrate the invention, I have shown on the drawing sealed delivery means 11 through 55

which a fluid from a suitable source (not shown) may be conducted to a receiver 13 adapted for relative rotation with respect to the fluid source. In the illustrated embodiment, the rotatable receiver 13 comprises a hollow drum having cylindrical wall portions 15 and end walls 17, the drum being suitably supported for rotary movement, as in bearings. Rotary receivers of this general character are found in many industries and frequently require the delivery of fluid to the receiver from a stationary source while the receiver rotates with respect to such source, and my present invention proposes means having manifold novelties and advantages for delivering fluid, such as cooling water, to the receiver, regardless of the form, construction and arrangement of the receiver, my invention, of course, being not in any way restricted to the construction of the receiver or the manner in which it is mounted for rotation and rotated in its mounting.

The liquid delivery means 11 of my present invention preferably comprises a pipe or conduit 21 having an end formed for connection with the hollow receiver 13. This connection, of course, may be made in any suitable fashion, preferably providing fixed connection of the pipe and receiver. I prefer, however, to form the receiver end of the pipe 21 with screw threads 23 adapted to sealingly fit into a threaded opening formed in the receiver 13, preferably in the end wall 17 thereof, in coaxial alignment with the rotary axis thereof. Outwardly of the threaded end portion 23 the pipe is or may be formed with flattened portions 25 affording a means for gripping the pipe, as with a tool, in threading the same into the receiver 13.

The end of the pipe 21 opposite the end carrying the screw threads 23 extends within a housing or casing 27 having a preferably cylindrical cavity at one end and a fluid-receiving chamber 29 in alignment within the casing, a cylindrical cavity and chamber being separated in the casing by an annular rib 31 formed preferably integrally and within the casing 27. The annular rib or ridge 31 forms an opening 33 to and into which the end of the pipe 21 extends.

The casing 27 is formed with a boss 35 having a threaded opening for the reception of a supply conduit preferably in coaxial alignment with the opening 33 and the pipe 21. The casing 27 preferably has an additional boss 37 likewise containing a preferably threaded opening into the chamber 29 in a direction radially of the axis of the pipe 21, so that fluid supply conduit means 39 may

be connected in either of the bosses 35 or 37, the opening in the other, of course, being suitably plugged with a threaded stopper, or supply conduits may be connected in both bosses.

As shown in Figure 1, the conduit means 39 comprises a stub pipe 41 tightly threaded in the embossment 37 and having a portion projecting outwardly of the embossment in position to receive a preferably flexible hose 43, one end of which is secured, as by a suitable clamp 45, upon the projecting end of the stub pipe 41, the other end of the hose 43 being connected in communication with a fluid supply source, such as a stationary water main.

Liquid delivered through the flexible hose 43 into the chamber 29 may escape thence through the pipe 21 and into the rotating receiver 13, and I provide in the casing 27 means for resiliently journalling the pipe within the casing and for sealing the pipe and casing against the escape of liquid from the chamber 29 between the outer surfaces of the pipe and the enclosing portions of the casing.

It will be noted, by thus journalling the casing 27 on the pipe 21 and by fixedly securing the pipe on the rotating element 13, the casing being connected with the source of fluid supply through a flexible hose connection 43, that the casing 27, although relatively stationary with respect to the pipe 21, is nevertheless entirely supported and sustained in position on the pipe by the rotating device 13. The casing 27 is thus able to follow any eccentric movement imparted to the pipe 21 during rotation as a result of faulty alignment of the pipe with respect to the axis of rotation of the receiver 13, or inaccuracies in the bearings on which the receiver 13 is supported. The arrangement thus facilitates and promotes adequate sealing of the conduit 21 within the chamber 27 and eliminates the difficulties of sealing the pipe 21 in a rigidly supported casing.

To journal and seal the casing 27 upon the pipe 21, I provide seal means comprising one or more bearing elements 51 in which the pipe 21 is journalled, and one or more resilient, preferably rubber-like elements which may conveniently comprise synthetic rubber, by means of which the bearing elements are resiliently held in place in the casing 27.

The bearing means 51 preferably comprises a material suitable for operation as a bearing on contact with moisture, and I prefer to use carbon for this purpose. Other suitable bearing materials having the desired characteristics, however, may, of course, be employed.

The bearing element 51 comprises a cylindrical portion 55 and an annular flange portion 57 formed preferably integral with and at one end of the cylindrical portion to form an element having substantially L-shaped sectional configuration. The outside diameter of the cylindrical portion 55 is slightly smaller than the diameter of the opening 33, while the inside diameter of the element is such that the same may form a journal for the pipe 21.

A journal element 51 is assembled with its cylindrical portion 55 extending in the opening 33 at the inner end of the pipe 21 with a resilient gasket 53 received between the annular rib 31 and the flange 57 of the bearing element, so that said element is resiliently supported in the casing by the annular mounting element 53.

In Figure 1 of the drawing I have illustrated a seal embodying two bearing elements 51. In this embodiment the pipe 21 is formed with an

outstanding annular flange 59 spaced from the inner end of the pipe 21 a distance equal to the length of the bearing element 55 so that one side of the flange 59 bears on the end of the bearing element opposite the end thereof that extends in the opening 33. The second bearing element 51 is assembled on the conduit 21 in position such that its flanged end bears against the side of the flange 59 so that said flange 59 extends between the flanged ends of the bearing elements 51, thereby forming a thrust bearing.

I prefer to provide, also, a spacing ring 61 of any suitable, preferably metallic material extending between the peripheral edges of the flanged ends of the bearing elements 51, the ring 61 fitting snugly within the pipe containing chamber of the casing.

The cylindrical portion 55 of the bearing element remote from the end of the pipe carries a resilient gasket 53 which extends between said cylindrical portion of the bearing element and the inner wall of the chamber in the housing 21. This resilient gasket is held between the flanged end of the bearing element and a holding ring 63 of any suitable material.

Both of the bearing elements 51 are thus mounted resiliently within the casing 27 by means of the yielding packing elements 53, and all of the elements, including the bearing and packing elements and the spacing and retaining elements 61 and 63, are held in place with the packing elements under slight compression by means of a retaining sleeve 65 which presses upon the retaining ring 63, fitting within the casing 27 and held in place by the annular cap ring 67 which is applied to the end of the housing and retained in place in any suitable fashion, as by the holding screws 69.

Leakage from the chamber 29 between the bearing elements 51 and the casing is prevented by the resilient mounting gaskets 53 which, being under slight compression, form tight fluid seals, and at the same time resiliently mount the bearing elements in self-aligning fashion. Leakage along the pipe between its outer surfaces and the bearing elements 51 is prevented by means of a seal assembly 81, which is mounted on the shaft between the end of the outer bearing element 51 and retaining means 83 on the pipe 21.

The sealing means 81 comprises a seal ring 83 of any suitable bearing material adapted to encircle the pipe 21 in position to bear upon and form a running fit with a seat provided at the facing end of the bearing element 51. The seal 83 also comprises an annular sealing gasket 85 of preferably soft flexible sealing material and having a cylindrical portion 87 adapted to snugly and frictionally engage the outer surface of the pipe 21. The annular sealing element 85 also comprises a portion 89 forming an annular flange at the end of the cylindrical portion 87 in position to lie against the ring 83 to form a seal therewith. The element 85 preferably comprises synthetic rubber, although any suitable rubber-like or suitable flexible sealing material may be used.

The sealing elements 83 and 85 are preferably, though not essentially, secured together in a fashion tending to prevent relative rotation therebetween. To this end I provide a preferably sheet-metal, retaining shell 91 having a cylindrical portion adapted to embrace the peripheral surfaces of the ring 83 and the flanged portion 89, and an inwardly extending annular flange 93 adapted to embrace the back of the flanged portion 89.

The inwardly extending flange 93 of the retain-

ing shell serves as a seat or bearing plate for receiving the thrust of one end of a spring 95 adapted to encircle the pipe 21 and bear at one end upon the back of the flanged portion 89 through the flange 93 operating as a thrust plate, the opposite end of the spring 95 bearing upon a collar 97 which is held in place upon the pipe 21 by means of the holding member 83'.

It will be noted that the resilient sealing element 85 has a substantially L-shaped sectional configuration. It will be noted, also, that the force of the spring 95 is applied to the outer or peripheral portions of the flange 89 which may thus have a substantially diaphragm action to accommodate any relative axial movement of the pipe with respect to the bearing element 51 against which the ring 83 forms a running fit.

In order to increase the sealing effect of the cylindrical portion 87 upon the outer surfaces of the pipe 21, a holding band 99 may be applied thereon in order to squeeze the same tightly upon the pipe.

It will be seen from the foregoing that I have provided adequate, though resiliently mounted, bearing means 51 for journalling the casing 21 upon the pipe, at the same time sealing the assembly against leakage of liquid between the bearings 51 and the casing, through the action of the yielding packing 53 applied under slight compression. Leakage of liquid through the bearings 51 is prevented by the running seal provided between the ring 83 and the facing end of the bearing 51, and leakage is prevented along the pipe through the ring 83 by means of the packing 85 which, being of elastic, rubber-like material, tightly grips the pipe by the cylindrical portions 87 of the seal, and the flanged portions 89 thereof are firmly pressed into sealing engagement with the ring 83 by means of the spring 95, which at the same time urges the seal assembly 81 in a direction on the pipe to maintain the running seal between the elements 51 and 83 at all times effectively tight. This effective tightness is maintained, regardless of relative wobble of the casing 21 with respect to the pipe, because the bearings 51 are yieldingly mounted in the casing and are to a degree self-aligning, while the seal ring 83 also has self-aligning characteristics because of the flexible diaphragm action of the flange 89.

The construction provides mechanical support for the casing 21 from the rotating receiver 13 through the pipe 21, the casing 21, however, remaining relatively stationary, while the pipe 21 may rotate within the casing, thereby permitting the casing to be connected with a stationary source of fluid from which it may be desired to deliver liquid into the receiver 13.

It is thought that the invention and numerous of its attendant advantages will be understood from the foregoing description, and it is obvious that numerous changes may be made in the form, construction and arrangement of the several parts without departing from the spirit or scope of the invention, or sacrificing any of its attendant advantages, the form herein described being a preferred embodiment for the purpose of illustrating the invention.

The invention is hereby claimed as follows:

1. A seal for coupling a pipe and a casing having a cavity defined by cylindrical wall surfaces and enclosing an end of the pipe, comprising a sleeve bearing and an additional bearing arranged in the casing in position encircling the

pipe, said bearings each having a pipe engaging portion and a peripheral mounting portion extending radially outwardly and fitting within the cylindrical wall surfaces of the casing, means cooperatively associated with said mounting portions for maintaining the bearing in axially spaced relationship in the casing, means carried by said sleeve bearing and forming an annular seal seat, an annular seal ring adapted for mounting on said pipe in position to engage and form a running seal with the seat, and resilient means frictionally engaging the seal ring and said pipe to drivingly connect and seal the ring and pipe together.

2. A seal for coupling a pipe and a casing as set forth in claim 1, including resilient gasket means sealing the space between the casing and the means forming the seal seat.

3. A seal as set forth in claim 1, wherein the pipe is formed with an integral outstanding flange extending between and engaging the facing ends of the pipe engaging portions of the bearings.

4. The combination of a hollow shell having an open end, an internal annular shoulder extending inwardly in said shell in position spaced from and facing said open end to define in said shell a bearing chamber and a receiving chamber on opposite sides of said shoulder, a pipe extending in said bearing chamber and having an inner end disposed substantially at said shoulder in position opening upon said receiving chamber, the opposite end of said pipe extending outwardly of the open end of said bearing chamber, means in said bearing chamber interconnecting the shell and pipe for relative rotation the one with respect to the other and to seal against fluid leakage through said bearing chamber, outwardly of said pipe, between said receiving chamber and said open end of the shell, said means comprising a resilient gasket on said shoulder, a sleeve bearing turnably supporting the inner end of the pipe and having a portion extending within said gasket and a remote portion formed with an outstanding flange enclosing and compressing said gasket on the internal annular shoulder of said shell, an additional bearing spaced from said sleeve bearing and turnably supporting said pipe in said bearing chamber, one of said bearings forming an annular seal seat, an annular seal ring on said pipe, and resilient means normally urging said seal ring on said pipe in a direction to engage and form a running seal with said seat.

5. The combination as set forth in claim 4 including a seal gasket of resilient rubber-like material having a tubular portion encircling and gripping the pipe adjacent the seal ring, and an annular integral flange portion engaging the seal ring, said resilient means holding the flange portion of the seal gasket in firm sealing engagement with said seal ring.

6. The combination as set forth in claim 4 including a seal gasket of resilient rubber-like material having a tubular portion encircling and gripping the pipe adjacent the seal ring, an annular integral flange portion engaging the seal ring, and a cage comprising an annular portion engaging the peripheral portions of the seal ring and gasket flange to hold the same in axial alignment, said cage including an inturned rim overlying the ring remote face of said gasket flange.

WALTER W. MEYER.
